UNITED STATES PATENT OFFICE

128,274

DESIGN FOR A FLASHLIGHT OR SIMILAR ARTICLE

Lynn Brodton, Collingswood, N. J.

Application April 28, 1941, Serial No. 100,659

Term of patent 14 years

To all whom it may concern:

Be it known that I, Lynn Brodton, a citizen of the United States and a resident of Collingswood, in Camden County, State of New Jersey, have invented a new, original, and ornamental Design for a Flashlight or Similar Article, of which the following is a specification, reference being had to the accompanying drawing, forming a part thereof, in which

Figure 1 is a perspective view of a flashlight or similar article showing my new design;

Fig. 2 is a front elevational view thereof;
Fig. 3 is a rear elevational view thereof; and
Fig. 4 is a side elevational view thereof, on a smaller scale.

I claim:

The ornamental design for a flashlight or similar article, as shown.

LYNN BRODTON.
